UNITED STATES PATENT OFFICE.

ALICK CLARKSON, OF EAST COWES, ISLE OF WIGHT, ENGLAND, ASSIGNOR, BY DIRECT AND MESNE ASSIGNMENTS, TO S. E. SAUNDERS LIMITED, OF EAST COWES, ISLE OF WIGHT, ENGLAND.

SEWING MACHINE.

Application filed March 14, 1922, Serial No. 543,604, and in Great Britain March 18, 1921.

This invention relates to sewing machines and more particularly those of the kind employed for performing heavy work such, for instance, as sewing or stitching together 5 sheets of ply-wood as described in the specification of former Letters Patent #1,444,482, of Feb. 6, 1923.

Owing to the inertia of the ply-wood, it 10 is found that, when feeding the latter intermittently in the usual way, with the machine running at a high speed, it tends to move when the needle is in it so that the latter is liable to break or bend.

My invention has for its object to ob- 15 viate this disadvantage and to this end I arrange to feed the material being stitched continuously instead of intermittently as heretofore, means being provided for moving the needle with the work at exactly the same 20 speed during its engagement therewith.

In a suitable arrangement for carrying out my invention I provide two pairs of rollers for gripping the material being sewn, one pair being in front of the needle and 25 the other pair behind the same. These rollers are mounted on shafts driven by suitable worm and bevel gears from the main shaft, the shafts being constructed so that the rollers can be adjusted to different thick- 30 nesses of material to be sewn. The lower shafts are carried at the forward end in adjustable bearings, whilst the forward bearings for the upper shafts are provided with extensions sliding vertically in guides 35 against the pressure of springs.

For moving the needle with the work, I provide a frame in which the needle bar and a presser foot slide vertically. This frame is formed with lateral extensions at the 40 lower part sliding in horizontal guides, the upper part of the frame sliding in a slot. The said frame is moved to correspond with the feed movement of the work, by a cam on the main shaft or on a separate shaft driven 45 by gearing from the latter, which cam actuates the frame through the medium of a lever and link, the needle bar being driven vertically by the usual crank and connecting rod.

50 The feed movement may be in either direction so that when a length of material has been stitched, instead of it being returned to the starting point to make a fresh line of stitching this latter may be made in the

reverse direction. For this purpose a reversing gear is employed for rotating the machine in the opposite direction and an additional cam is provided for effecting the correct movement of the take-up lever, suitable mechanism being provided for throwing one cam into gear and the other out of gear.

To enable the invention to be fully understood, I will describe it by reference to the accompanying drawings, in which:—

Figure 1 is a front elevation of a sewing machine constructed in accordance with my invention and designed to feed the work in one direction only.

Figure 2 is a side elevation of the machine 70 with a part thereof removed.

Figures 3 and 4 are horizontal sections on the lines 3—3, and 4—4, Figure 1, respectively.

Figure 5 is a rear view of a part of the 75 machine showing the driving gear for the feed rollers.

Figures 6 and 7 are, respectively, a side elevation and an end view showing the framing of the machine more clearly than is 80 indicated in the preceding figures.

Figure 8 is a sectional side view showing a modification of the mechanism for operating the take-up lever to allow the latter to function when the feed of the work is reversed 85 for each alternate line of stitching.

Figure 9 is a section on the line 9—9, Figure 8.

The frame of the machine comprises the base *a*, the upright *b* and the neck or bracket *c* extending from the upright *b* and overhanging the base *a*, the said neck carrying in suitable bearings the shaft *d* for operating the needle-bar *e* by a crank disc *e*¹ and connecting rod *e*² whilst the base *a* carries the driving shaft *f* and an oscillatory shuttle *f*¹ co-operating with the needle *g* of the needle-bar *e*. The shuttle is rocked from the shaft *f* by suitable gearing, not shown. The shaft *f* drives the shaft *d* through the medium of the vertical shaft *f*² and suitable gearing, not shown, and carries clutch mechanism *f*³ whereby it can be started and stopped. *h* is the usual take-up lever for the needle thread, operated by a cam-groove 105 *h*¹ in the periphery of the crank-disc *e*¹.

i, *i*¹, *i*², *i*³ are the two pairs of feed rollers for the material to be sewn, for instance,

ply-wood and indicated by the dot and dash lines A, Figure 1, the members of each pair gripping the said material between them, and each roller being formed in two parts which 5 are arranged one on each side of the supporting bearing of the shaft therefor. The pair of rollers i are arranged at the front of the needle g whilst the pair of rollers i^1 are behind the said needle. j, j, j^1, j^1 are the 10 shafts carrying at one end the rollers i, i, i^1, i^1 , respectively, whilst their other ends are geared together by gear-wheels i^2 of equal diameters and one of each pair is driven from the shaft f^2 by worm gearing β^3 as 15 indicated in Figure 5. k, k are the bearings for the ends of the shafts j and j^1 carrying the lower rollers i, i^1 the said bearings being mounted on the base a through the medium of the threaded studs k^1 , the holes in the 20 bearings through which the said studs pass being elongated to allow of the position of the said bearings being adjusted. l, l are the bearings for the shafts j, j^1 carrying the upper rollers and l^1, l^1 are the extensions there- 25 on which slide vertically in guide-ways l^2 on blocks l^3 attached to the part c of the frame, against the pressure of the springs l^4 . These springs encircle rods l^5 which extend upwardly from the extensions l^1 and 30 slide in guides l^6 also on the bracket c , the said springs being located between shoulders on the rods l^5 and the undersides of the said guides. To enable the upper feed rollers i, i^1 to be lifted to allow the material 35 A to be placed in position on or removed from the lower feed rollers, a pair of lever- arms m connected at their outer ends by a cross bar or handle m^1 are pivotally connected at m^2 to the rods l^5 and fulcrumed 40 at m^3 to the one end of links m^4 the other ends of which are pivoted at m^5 to the guides l^6 . By raising the handle m^1 in the direction of the arrow, Figure 2, it will be seen that the upper rollers i, i^1 will be raised, 45 the parts being locked in this position when the arms m attain the position indicated by the dot and dash lines in the said figure, the three centers m^2, m^3, m^5 being practically in alignment. The shaft j and j^1 are formed 50 in sections connected by universal joints j^2 to allow of vertical movement of the rollers i, i^1 .

n is the frame in which the needle-bar e and spring pressed presser foot n^1 slide vertically and n^2, n^2 are the lateral extensions 55 on the lower part of the said frame which are slidably mounted in horizontal guide-ways n^3 in the blocks l^3 , the upper part of the frame n being formed with a horizontally disposed portion or head slidably arranged in a horizontal guide slot o , formed between a pair of guide-bars o^1 carried by the bracket c .

The frame n is moved horizontally, when 60 the needle g is in the work A, in corre-

spondence with the feed movement of the rollers i, i^1 so that no side strain is exerted on the needle to break or bend it, this horizontal movement of the said frame being effected by an irregular cam groove p in the 70 face of a disc p^1 on the shaft d through the medium of a lever q fulcrumed at q^1 in a bracket q^2 on the neck c , one end of the said lever engaging the said groove by a roller q^3 whilst the other end of the lever is connected to the frame by a connecting-rod q^4 . The course of groove p in disc p^1 is such that during the portion of the upward movement of the needle, when it is free of the material A it moves in the reverse direction 80 to that of the said material and this reverse movement finishes at the time the needle again enters the material with which it again moves forwardly and so on. It will thus be seen that the lateral movement of the needle 85 corresponds with the movement of the work during its entire engagement therewith.

r is a small circular cutter or saw arranged in front of the needle for forming grooves in the known manner in the upper surface of 90 the material A for the upper or needle thread to lie in, this saw being mounted on a spindle r^1 carried in bearings in an arm r^2 pivoted to the front upper bearing l . The said spindle is rotated by a sprocket wheel s driven 95 by a chain s^1 from a sprocket wheel s^2 on the shaft d the spindle s^3 carrying this sprocket wheel being mounted in bearings in a bracket t mounted on the neck c and connected to the spindle r^1 by an intermediate 100 spindle and universal joints r^3 .

The machine above described is arranged to feed in one direction only so that the material A, when a line of stitching is made therein, has to be returned to the starting 105 point to make the next line of stitching.

I may, however, arrange to feed the material in the reverse direction to that described above to avoid the described return movement, and for this purpose the driving shaft f is arranged in connection with mechanism whereby its rotation can be reversed so as to reverse the movement of the feed rollers i, i^1 . As this reverse movement of the shaft f will result in a corresponding movement of the shaft d it is necessary to provide means for effecting the correct movement of the take-up lever for both directions of the said shaft d . For this purpose I employ the arrangement illustrated in Figures 8 110 and 9 wherein the cam h^1 is dispensed with and a pair of connected cams u, u^1 are keyed to but slidably mounted on a cross-shaft v driven by spiral gear v^1 from the shaft d so that either of the cams can be brought by 115 suitable mechanism, not shown, beneath the take-up lever, the latter then resting thereon and being operated thereby. These two cams are of shapes which will give the appropriate movement to the take-up lever ac- 120 125 130

cording to the direction of the feed rollers *i, ii*.

I claim:

1. In a sewing machine for sewing heavy material, the combination with a continuous feed mechanism for the material being stitched, of a stitch forming mechanism having an upright and straight needle movable vertically and laterally, the needle during the lateral movements being truly vertical and moving with the work at exactly the same speed during its entire engagement therewith.

2. A sewing machine as claimed in claim 1, wherein the means for moving the needle laterally comprise a needle bar, a needle bar frame in which the needle bar is vertically reciprocated and which is slidably mounted in horizontal guideways to keep the needle at all times vertical and in line with the stitching, and means for imparting lateral movement to the needle bar frame.

3. A sewing machine as claimed in claim 1, wherein the means for moving the needle laterally comprise a needle bar, a needle bar

frame in which the needle bar is vertically reciprocated and which is slidably mounted in horizontal guideways to keep the needle at all times vertical and in line with the stitching, and means for imparting lateral movement to the needle bar frame, said means comprising a cam formed to give the correct progression while the needle is in engagement with the work and a quick return while out of engagement therewith. 30 35

4. A sewing machine as claimed in claim 1, wherein selectively operated means are employed to actuate the take-up lever so that the machine can be run in either direction. 40

5. A sewing machine as claimed in claim 1, wherein selectively operated means are employed to actuate the take-up lever so that the machine can be run in either direction, said means comprising a pair of connected cams, which are respectively engaged with the said lever according to the direction in which the machine is being run. 45

ALICK CLARKSON.
